APPARATUS FOR SECURING UNIFORM DRYING OF THE SHEET IN PAPER MAKING MACHINES

Arthur E. Broughton, Neenah, Wis.

Application September 16, 1935, Serial No. 40,754

5 Claims. (Cl. 34—48)

This invention relates to paper making processes and machines. More specifically, it relates to methods and apparatus for uniformly controlling the moisture content of the paper sheet as it is dried in a paper making machine.

It is an object of the present invention to provide novel and improved methods and apparatus for controlling the moisture content of the paper sheet as it passes over the drying cylinders of a paper making machine, so as to secure even and uniform drying of the sheet irrespective of variance in the sheet formation and to also secure at the dry end of the machine a sheet having the desired uniform moisture content.

More specifically, it is an object of the invention to maintain substantially uniform moisture content in the sheet at the dry end of a paper making machine by maintaining substantially constant steam pressure in certain of the drying cylinders of the machine through regulating the supply of steam to the certain drying cylinders by slight variance in the steam pressure in said certain cylinders above and below the said constant and increasing or decreasing the supply of steam to the other cylinders as the supply of steam to the certain cylinders is increased or decreased.

It is a further object to maintain proper steam pressure on the various drying cylinders of a paper making machine for even and uniform drying of the sheet by steam supply control mechanism automatically operated by the pressure of steam in one or more of the drying cylinders located most closely adjacent the wet end of the machine.

The objects and advantages of the invention will more fully appear from the following description, made in connection with the accompanying drawings, wherein like reference characters refer to the same or similar parts throughout the various views, and, in which,

Fig. 1 is a diagrammatic view in side elevation illustrating portions of a paper making machine incorporating therein apparatus embodying the invention, and

Fig. 2 is a view partly in side elevation and partly in vertical section illustrating in an enlarged scale certain of the parts shown in Fig. 1.

Referring to the drawings, the floor of a paper mill is designated by the numeral 3. Above this floor there are shown a number of the drying cylinders or driers of a paper making machine. A group of these driers located most closely adjacent the wet end of the machine (four driers in the illustrated embodiment) are designated by

the numeral 4, while the remaining driers, for the purpose of distinction, are designated by the numeral 5.

A steam supply conduit 6 for supplying the various driers 4 and 5 is shown and this conduit is directly connected to the driers 5 by individual auxiliary conduits 7. The steam supply conduit 6 has a branch conduit 8 connected thereto forward of the auxiliary conduits 7. The branch conduit 8 is provided with a horizontal portion 10 and it is connected to a header 9 from which steam is supplied to the various driers 4 through auxiliary conduits 10.

Between the point where branch conduit 8 connects with the steam supply conduit 6 and the point where the first or left hand auxiliary conduit 7 connects with the steam conduit 6, a control valve 11 is provided in the conduit 6 for hand regulation of the steam supplied through the conduit 6 to the driers 5. The stem 11a of valve 11 may be pivotally connected to a lever 12 pivoted at one end on a fulcrum 13 secured to the valve, and having connected at its other end an upwardly extending cable 14. Cable 14 passes through a tube 15 in floor 3 and is attached at 17 and adjustable in length to and from lever 12 by means of thumb screw 18. Of course, other means may be employed for adjustably setting the valve 11.

Return lines 19 for carrying off the air and the water condensed from the steam in the various driers 4 and 5 are provided and these return lines run downwardly to check valves 20 connected to a water return pipe 21.

A by-pass 22 about the valve 11 is provided in the steam supply conduit 6. This by-pass 22 may be in the form of an inverted U-tube as shown, having one leg connected to the steam supply conduit 6 between valve 11 and branch conduit 8 40 and another leg connected to the steam conduit 6 between valve 11 and the first or left hand auxiliary conduit 7. In the horizontal portion of the U-tube forming by-pass 22 is located a control valve 23 which closes on down movement 45 of its valve stem 23a and opens on up movement of its valve stem. Pivotally connected to valve stem 23a is one end of a lever 24 pivotally mounted on a fulcrum 25 attached to valve 23 and carrying a weight 26 adjacent its end opposite the end pivoted to valve stem 23a. The lever 24 near its weighted end is provided with a sliding rider 24a to which an upwardly extending chain or cable 27 is connected. A set screw 24b carried by the rider is used for adjustably se- 55

curing the rider 24a to the lever 24 in a desired adjusted position.

Mounted in the horizontal portion of branch conduit 8 is a control valve 28 which closes on upward movement of its valve stem 28a and opens on downward movement of the said stem. The valve stem 28a is pivotally connected to a lever 29 pivoted on a fulcrum 30 mounted on valve 28. Mounted on the right end portion of lever 29, as viewed in the drawings, is a weight 31, while the upper end of cable 27 is connected to the left end of the lever. Lever 29 carries near its left end a sheave 32.

Mounted on the floor 3 is a type of manometer, which may be designated as an entirety by the letter A. This manometer may take various forms but in the illustrated form, manometer A is located below the sheave 32 and, it includes outer and inner stand pipes 33 and 34, respectively. The outer stand pipe 33 is closed at its lower end and a closure ring 35 is provided between the inner and outer stand pipes at their upper ends. The inner stand pipe 34 is supported from the ring 35 so that the lower end of the inner pipe is disposed slightly above the bottom of the outer stand pipe 33. Both the upper and lower ends of the inner pipe are open. About midway of the height of the stand pipes a partition 36 in the form of a flanged ring is provided between the two pipes and mounted in this partition are a number of small vertically extending tubes 37 projecting above the partition and open at both ends. A drain pipe 38 is connected to the outer stand pipe 33 to communicate therewith immediately above the partition 36 and this drain pipe runs downwardly to form a U-shaped water trap portion 38a and then connects with one of the auxiliary conduits 10 through a check valve 38b. Below the partition 36 another drain pipe 39 connects at one end to the outer stand pipe 33 so as to communicate at one end therewith and the other end of the drain pipe 39 is connected to drain pipe 38.

A float 40 fits within the inner stand pipe 34 and this float has connected to its upper end one end of a chain or cable 41 which runs upwardly over sheave 32 and then downwardly along side of the outer stand pipe 33. The end of the chain or cable 41 not connected to float 40 has a pin 42 secured thereto and this pin is adapted to be received within any one of a number of vertically spaced pin receiving openings 43 formed in a vertical adjustment board 44 secured as by legs 45 to the floor 3. Normally water or other liquid stands within the inner stand pipe 34 so as to at least partially buoy up the float 40 to relieve the lever 29 partially of the weight of this float. Lever 29 is so weighted by the weight 31 relative to the float 40 that as the height of liquid within the inner stand pipe 34 raises from a given position somewhat to further buoy up the float 40, the left end of the lever 29 is relieved of at least part of the weight of the float and the weight 31 will then depress the right end of the lever 29 somewhat to raise the left end of the lever and thereby raise valve stem 28a and close valve 28 to a greater extent than formerly. At the same time that this action occurs, the chain or cable 27 will be raised somewhat to thereby raise the right end of lever 24 against the force of weight 26 and depress the left end of lever 24, thereby depressing valve stem 28a and moving the valve 28 to a more nearly closed position. As the column of liquid within the inner stand pipe 34 lowers somewhat from a

certain height, the float 40 exerts more weight upon the left end of lever 29 by reason of the fact that the liquid within the stand pipe 34 does not buoy up the float to the same extent. The increased force exerted by the float 40 on the left end of lever 29 will be sufficient to overbalance the weight 31 slightly and depress the left end of lever 29 somewhat, thereby depressing valve stem 28a and opening valve 28 to a greater extent. As the left end of lever 29 is depressed somewhat, the right end of lever 24 may swing downwardly somewhat under the influence of the weight 26 and, as a result, the left end of lever 24 will rise to slightly raise the valve stem 28a and thereby open the valve 28 to a greater extent than formerly.

A water glass 46 for showing the level of liquid within the outer stand pipe 33, is preferably connected at spaced points to this pipe below partition 36.

A steam pipe 47 affords communication between header 9 and the upper part of the stand pipe 33. If desired, a pressure gauge 48 may be connected to the pipe 47.

In preparing the equipment for operation, liquid such as water is introduced into the manometer A through the open inner end of the inner stand pipe 34 when no steam is being supplied to the driers 4 and 5, i. e. when the manometer is subject to only atmospheric pressure. At length, the water level will rise in both the inner stand pipe 34 and in the outer stand pipe 33 to the point 49 where the drain 39 connects with the outer stand pipe 33. The point 49 may be referred to as the neutral point, inasmuch as columns of liquid within both stand pipes 33 and 34 will stand at the point 49 when the driers 4 are under atmospheric pressure. If more liquid is originally introduced into the manometer A than sufficient to raise the level of the columns of liquid within the two pipes 33 and 34 to the neutral point 49, the surplus liquid will drain off through drain 39 so that the level of liquid in both pipes will stand at the neutral point 49 under atmospheric pressure.

Prior to using the equipment, valve 11 will be set by adjustment of thumb nut 18 so as to supply the major portion of the steam for the driers 5 from the main supply conduit 6 through valve 11. Of course, additional steam will be supplied to these driers 5 through by-pass 22 and valve 23, the quantity of additional steam supplied being dependent on the extent to which valve 23 is open at any given time. The steam supplied to the driers 4 from the conduit 6, conduit 8, header 9 and auxiliary conduits 10 will be dependent upon the extent to which valve 28 in conduit 8 is open. The rider 24a will be slid along the lever 24 and secured to the lever in a desired adjusted position by the set screw 60 24b for a purpose presently to appear.

Pin 42 will be plugged into one of the pin receiving openings 43 of the board 44 to set the mechanism for maintaining a desired steam pressure in the driers 4. If it is desired to maintain the driers 4 under low steam pressure, the pin 42 will be plugged into one of the upper pin receiving openings, while if it is desired to maintain the driers under higher steam pressure, the pin 42 will be plugged into one of the lower pin 70 receiving openings 43. Sufficient of the openings 43 are provided at vertically spaced intervals that the pin 42 may be plugged into an opening 43 to maintain the driers 4 under any desired steam pressure required in producing all 75

kinds of paper that may be made with the paper making machine.

Let us assume that the manometer has been properly filled with a liquid such as water so that a chamber 50 is formed in the manometer A between the outer and the inner stand pipes 33 and 34 respectively, between the closure ring 35 and the level of water in the outer stand pipe 33, and let us further assume that the pin 42 has been plugged into the fifth pin receiving opening 43 from the top of the board 44 to maintain the driers 4 under two pounds steam pressure, the desired steam pressure in these driers for production of the particular paper to be now made by the machine. The gases in the chamber 50 may, of course, freely communicate above and below partitions 36 through the small tubes 37. Inasmuch as the driers 4 are connected to the header 9 by the auxiliary steam conduits 10 and the header 9 is in communication with chamber 50 of the manometer through the pipe 47, it will be seen that the same pressure will be maintained at all times within the chamber 50 as is maintained in header 9. It is preferable to provide the header 9 and to connect the same through auxiliary conduits 10 with several of the driers 4 most adjacent the wet end of the machine rather than to communicate only one drier with the chamber 50, so that minor fluctuations of pressure due to conditions in only one or two of the driers 4 will only reflect on the pressure within the chamber 50 as they reflect on the pressure maintained on the group of driers 4 to which the header 9 is connected.

As the paper making machine is set in operation, and steam is supplied through the steam conduit 6, both valves 28 and 23 will remain practically wide open until the pressure of steam within the driers 4 has been built up to close to 2 pounds pressure, the pressure for which the manometer A has been set. As the steam pressure within driers 4 is built up nearly to 2 pounds pressure, the pressure within chamber 50 will be correspondingly built up to thereby depress the level of liquid within the outer stand pipe 33 and drive part of the liquid from the outer pipe into the inner stand pipe 34 to thereby raise the level of liquid within the inner pipe. At length, the liquid level within the inner stand pipe 34 will be raised to such an extent that the liquid will buoy up a considerable portion of the weight of the float 40 thereby relieving the lever 29 of that part of the weight of the float lifted by the liquid within the inner stand pipe 34. As the weight of the float 40 is relieved from the lever 29, the left end of the lever raises somewhat to cause closing movement of both the valve 28 and the valve 23. At length when sufficient steam is being supplied through the valve 28 to maintain the driers 4 under exactly 2 pounds pressure, the lever 29 will remain approximately stationary to hold valve 28 and valve 23 partially opened. In other words, the rise in steam pressure within the driers 4 will continue until the valve 28 closes sufficiently to continuously supply just the right amount of steam to driers 4 through conduit 6, conduit 8, header 9, and auxiliary conduit 10 to maintain driers 4 at the desired pressure for which the mechanism is set. If the pressure within the driers for any reason should temporarily rise slightly above this point, additional weight of the float 40 will be buoyed up by the resulting higher column of liquid within the inner stand pipe 34 and as a result the valves 28 and 23 will close somewhat to reduce the supply

of steam to the driers 4 and thereby lower the pressure therein back to normal. Similarly if for any reason the pressure of steam within the driers 4 should drop slightly below the pressure for which the mechanism is set, the level of liquid within the inner stand pipe 34 will drop slightly, thereby imposing more of the weight of the float 40 on the lever 29 to open the valves 28 and 23 to a slightly greater extent, and cause additional steam to be supplied through the valve 28 to the driers 4 to build up the pressure in these driers to the set point.

As the valve 28 moves to a more open position or as it moves to a more closed position, the valve 23 similarly opens or closes. As the valve 23 controls the supply of steam through by-pass 22 to the driers 5, it will be understood that as greater quantities of steam are supplied to the driers 4, greater quantities of steam will be supplied to the driers 5 and as less steam is supplied to the driers 4, less steam is supplied to the driers 5. The setting of the rider 24a on the lever 24 determines the extent to which the valve 23 is actuated as the valve 28 is actuated and by properly adjusting this rider on the lever 24 it is possible to correlate the supply of steam to the driers 4 and 5 so as to cause uniform drying of the sheet as it passes over the various driers, and to also secure at the dry end of the machine a sheet having the desired uniform moisture content. If the sheet as it passes over the various driers 4 contains greater or lesser quantities of moisture at one time than at another, or if the sheet becomes lighter or heavier or freer or slower as it passes over the driers 4, or if the speed of the machine varies, or if other conditions in the sheet formation vary as the sheet passes over the driers 4, this is immediately reflected in the rate of condensation of steam within the driers 4. The steam pressure within the driers 4, of course, tends to change as the rate of condensation changes within these driers. If, for example, the sheet carries more water as it passes over the driers 4 than previously, the increased moisture in the sheet will cool these driers more quickly, thereby causing more moisture to condense in the driers and a corresponding lowering of steam pressure in the driers. The automatic control mechanism immediately responds to this variation in pressure so as to supply more steam to the driers 4 to immediately build up the pressure in the driers 4 to the old constant pressure. If the sheet carries more water as it passes over the driers 4 than previously, it will also carry more water than previously as it passes over the driers 5 so as to also cool these driers more quickly through the increased condensation of moisture in the driers 5. As increased steam is supplied to the driers 4, increased steam through the by-pass 22 and valve 23 will be supplied to the driers 5 to remedy the condition in these driers.

It will be seen that there has been provided a simple process and apparatus for securing uniform drying of the sheet in a paper making machine and for securing uniform moisture content in the sheet at the dry end of the machine. This is done by utilizing the variance in steam pressure in certain of the driers of the machine above and below a desired constant for causing less or more steam to be supplied to these certain driers to quickly and almost immediately lower or raise the steam pressure within these certain driers back to the desired constant, while at the same time causing less or more steam to be supplied to the remaining driers. In other

words, if conditions arise in the formation of the sheet or in the operation of the machine that would otherwise effect uniform drying of the sheet or effect the uniformity of the moisture content in the sheet at the dry end of the machine, my method and apparatus will quickly adapt the drying cylinders to the changed condition, so that at all times the sheet will be uniformly dried and will contain the desired moisture content at the dry end of the machine. By automatically regulating the steam supplied to the various driers, the drying capacity of these driers is varied to adapt the driers to the sheet passing over the same. As the steam pressure on the driers 4 rises or falls below a desired constant, the supply of steam to these driers 4 is automatically reduced or raised to bring the steam pressure within these driers 4 back to the desired constant and this is done almost immediately. At the same time steam is supplied in lesser or greater quantities to the remaining driers 5, so as to reduce or increase the drying capacity of these driers 5 to meet the changed condition of the sheet.

25 By plugging in the pin 42 in different pin receiving openings 43 in the board 44, it is possible to vary the setting of the device so that the constant pressure to be maintained in the driers 4 can be changed to form various types 30 of sheets with the machine. By changing the position of the rider 24a on the lever 24, it is possible to change the proportionate opening and closing movement of the valve 23 relative to valve 28 so as to properly control the steam supplied to the driers 5 relative to the steam supplied to the driers 4.

By provision of the partition 36, the tubes 37 and the drain 38, steam carried over into the upper part of chamber 50 through steam pipe 40 47 and condensed into water within the chamber 50 will be drained off through drain pipe 38, so that the condensation of steam within chamber 50 will not raise the water level within the manometer and change the setting of the manometer. While the partition 36 and the tubes 37 prevent the passage of condensed water downwardly below the partition, the tubes 37 afford free communication between the different sections of the chamber 50 above and below the partition.

50 If at any time during the operation of the machine there should be a break in the sheet ahead of the driers 4, the steam pressure within these driers will, of course, immediately raise 55 to such a point as to cause the valve 28 to practically completely close and to also cause the valve 23 to practically completely close automatically, thereby preventing wastage of the steam until the sheet again begins to move over the driers. After the sheet again begins to pass over the driers 4, the manometer remains properly set for proper drying control.

55 Of course, other mechanisms and apparatus can be used for carrying out my method of securing uniform drying of the paper sheet as it passes over the driers of a paper making machine, and for securing uniform moisture content in the sheet at the dry end of the machine.

It will, of course, be understood that various 70 changes may be made in my processes and in the steps thereof and in the form, details, arrangement and proportions of the various parts

of the apparatus without departing from the scope of the present invention, which, generally stated, consists in the matter shown and described and set forth in the appended claims.

What is claimed is:

1. In a paper making machine, a plurality of driers over which the sheet passes, a steam line supplying said driers, valve mechanism regulating the supply of steam through said line, a manometer, a conduit communicating a certain section of said driers with the closed end portion of said manometer, a float mounted within the open end portion of said manometer to be buoyed up by the liquid within the manometer to a varying extent depending on the liquid level within the open end portion of the manometer, and means connecting said float with said valve mechanism to move said valve mechanism to more nearly closed position as said float is buoyed up by the liquid in said manometer to a greater extent and to move said valve mechanism to more nearly open position as said float is buoyed up to less extent by the liquid in said manometer.

2. The structure defined in claim 1, and means for varying the set level of said float in said manometer.

3. The structure defined in claim 1, and means for draining off any condensate from steam admitted to the closed end portion of said manometer.

4. In a paper making machine, a plurality of driers over which the sheet passes, a steam line for supplying all of said driers, a main valve controlling the supply of steam through at least 35 a portion of said line, a by-pass around said main valve, an auxiliary valve in said by-pass, a pressure responsive device for operating said auxiliary valve, means connecting said pressure responsive device to a certain section of said 40 driers most closely adjacent the wet end of the machine, said pressure responsive device acting to more widely open said auxiliary valve as the pressure in said certain section drops slightly below a certain constant and acting to tend to 45 close said auxiliary valve as the pressure in said certain section rises slightly above said certain constant.

5. In a paper making machine, a first group of driers and a second group of driers, said first group being located more closely adjacent the wet end of the machine than said second group, and the sheet passing over all of the driers of both groups, a steam supply conduit, means connecting said supply conduit to said second group 55 of driers, a header, means connecting said header to said first group of driers, a second conduit connecting said first mentioned conduit to said header, a first control valve in said first conduit, a second control valve in said second conduit, a manometer containing liquid, a tube communicating said header with the closed end of said manometer, a float mounted within the open portion of said manometer and mechanism operating said two valves from said float 65 in such manner that when the float is increasingly buoyed up by the liquid within the manometer said valves will move towards closed position and when said float is decreasingly buoyed up by the liquid within said manometer, the said 70 valves will move towards open position.

ARTHUR E. BROUGHTON.
